UNITED STATES PATENT OFFICE

LAURITS C. EICHNER, OF BLOOMFIELD, NEW JERSEY, ASSIGNOR TO DRESSEL RAILWAY LAMP & SIGNAL COMPANY, OF ARLINGTON, NEW JERSEY, A CORPORATION OF MAINE

SWITCH AND LAMP SUPPORT

Application filed January 6, 1928. Serial No. 244,989.

My invention relates to lamps and particularly to electric tail marker lamps such as are used on the rear ends of trains.

The invention particularly has for its object to provide a combined lamp support and automatic switch of such design and construction that the simple act of placing the lamp in position will effect the electrical connection necessary to energize the bulb of the lamp from the train circuit feed wires, and conversely the act of removing the lamp will open the circuit.

Further, the invention has for an object to provide a means to guard the switch terminals from accidental short circuits should one attempt to place a conducting object in the socket from which the lamp has been removed.

Further, the invention has for an object to provide a socket with a switch element having circuit contact members to receive the mating contact members of the lamp when the bracket is inserted in the socket.

Further, the invention has for an object to provide for the throwing of the switch to bring its contact terminals into position to receive the mating contact terminals of the bracket, throwing the switch upon the initial part of the inserting movement of the bracket member into the socket element, and for effecting the connection between the movable element's circuit terminals and the contact members of the switch during the latter part of the inserting movement.

Further, it is an object of the invention to provide a bracket with fixed circuit terminals and a switch, the latter having contact elements normally disengaged from said circuit terminals and adapted to be engaged therewith upon throwing the switch to a circuit closing position, the bracket element having provisions for throwing the switch to either of its positions and having relatively fixed circuit terminals to cooperate with the switch contacts, provision being made for first causing the switch to engage the fixed contacts of the bracket before the switch contacts are engaged by the circuit terminal members of the bracket, and conversely enable the bracket contacts to be disengaged

before the switch elements are disengaged from the socket contacts.

Further, it is an object to provide means to interlock the lamp bracket and socket elements when assembled and to provide sufficient lost motion between the same to enable the circuit connections to be effected as above referred to.

Further, the invention has for an object to provide a device of the character described in whose socket element provision is made whereby the bracket of an oil lamp may be placed in, and the lamp supported by, the socket in the event it becomes necessary to use an oil lamp due to failure of the electric circuits or other causes.

Other objects will in part be obvious and in part be pointed out hereinafter.

To the attainment of the aforesaid objects and ends, my invention consists in the novel details of construction and in the combination, connection and arrangement of parts, hereinafter more fully described and then pointed out in the claims.

In the accompanying drawings, showing illustrative embodiments of the invention,

Figure 1 is a perspective view showing my invention in use.

Fig. 2 is an enlarged side elevation of the socket member with a portion of the cover removed, the switch being in the circuit-open position.

Fig. 3 is a top plan view of the socket member shown in Fig. 2.

Fig. 4 is a vertical longitudinal section on the line 4—4 of Figure 3.

Fig. 5 is a vertical longitudinal section with the bracket element inserted a distance sufficient to throw the switch.

Fig. 6 is a vertical longitudinal section with the bracket element completely inserted.

Fig. 7 is a horizontal section on the line 7—7 of Fig. 6.

Fig. 8 is a detail rear elevation of the bracket member showing the position of its contact fingers.

Fig. 9 is a vertical cross section on the line 9—9 of Fig. 6.

Fig. 10 is a detail perspective view of the switch and its toggle rod.

Fig. 11 is a detail perspective view of an oil lamp bracket such as may be used with my socket member if desired.

In the drawings in which like numerals of reference indicate like parts in all the figures, 5 1 represents the socket member's base plate from the front of which the socket proper 2 projects. The socket proper 2 has a tapered opening 3, to receive a signal flag staff. It 10 is also provided with a slot 4 and a T slot 5 for the reception of the bracket of a lamp. The socket member is adapted to be sunk into its support and secured by screws passing through fastening ears 6.

15 The rear face of the member 1 is preferably vertically grooved as at 7 for a purpose later made clear. Pairs of upper and lower trunnion-bearing lugs 8 and 9 are provided on the back of the plate 1 to receive the 20 trunnions 11 which bear against the surface 10 under spring pressure as will later be clear.

The switch comprises a metallic face plate 12 having projections 13 to be engaged by the bracket member to throw the switch from one 25 position to another. The face plate 12 is also provided with a stop 14 and the face plate is designed normally to fit in a slot 25 in the base plate 1 and constitute a closure therefor.

30 The switch also includes an insulator 30 that is held to the face plate 12 in any suitable manner as by screws, or lugs 15 on which the insulator material may be molded. The face plate 12 is also provided on its rear portion with ears 16 between which on a suitable pivot 18 the head of the toggle rod 17 is mounted.

Embedded in the insulator 30 of the switch is a pair of circuit closer elements or plates 19 having spring contact fingers 21 at one 40 end and clip fingers 20 at the other end.

Mounted on suitable insulation supports 24 on the back of the base plate 1 are relatively fixed (and resilient if preferred) contact elements 22 with which the fingers 21 are adapted to engage when the switch is in 45 the circuit-closed position. The elements 22 are secured at 23 where the feed wires (not shown) of the train circuit are also adapted to be connected.

50 Extending rearwardly from the base plate 1 are suitable cover supporting arms 26, to the ends 27 of which the cover 28 is fastened by screws 29 or other suitable means.

55 31 designates the arm of the electric lamp bracket which has a mating portion 32 adapted to be received by the socket 2 and which has a flange 34 adapted to be received by the T slot 5 of the socket member, the arm 31 being grooved at 33 to clear the projections 60 39 on the front of the base plate 1.

The mating element 32 of the bracket is chambered at 35 while the arm 31 has a passage 36. In the passage 36 are located the circuit terminal bars by which the current is conducted to the lamp bulb socket (not shown).

The bars 37 are suitably mounted in insulation in the passage 36 to be relatively fixed, and they have fingers 38 adapted, when the bracket and socket members are assembled and the switch thrown to the circuit-closed position, to enter the clip fingers 20 and close the circuit therewith.

In using my invention the line wire terminals of the train circuit are connected at 23 to the contact fingers 22, the switch being 75 normally in the position shown in Fig. 4. Upon inserting the bracket element 32 into the socket proper the lower edge 40 will engage the projections 13 of the switch and press downwardly thereon, thereby turning the 80 switch on its trunnion 11 in a counter-clockwise direction in Fig. 4 to throw the switch toward its circuit-closed position. As soon as the switch has been thus moved a distance sufficient to bring the pivot pin 18 above the 85 trunnion 11 the spring actuated rod 17 will complete the throw of the switch quickly and bring the contacts 21 and 22 together before the fingers 38 begin to enter the clips 20. Further downward movement of the 90 member 32 in the socket brings the fingers 38 into the clips 20 and completes the downward movement until 31 rests on 2. When in this 95 position the switch will be projected into the chamber 35 and interlocked with the member 32.

Reversing the movement of the bracket to remove the lamp first causes the fingers 38 to be disengaged from the clips 20 and then the bottom 40 of the member 32 will engage the plate 12 to turn the switch in a clockwise direction in Fig. 6, thereby moving the switch back toward the circuit open position, the movement being completed with a quick action 105 as soon as the pivot 18 passes the axis of the trunnions 11.

Should perchance the electric current fail and it becomes necessary to use an oil lamp, the bracket 2 is so designed as to permit this to be done. The mating member 41 and web 42 of the oil lamp bracket (see Fig. 11) will fit the openings 3 and 4 as in the usual oil lamp type brackets.

Also the present type of electric tail marker lamps in which the circuit is made by a cord connection and which has a separate bracket, may be mounted on my socket in case the train is equipped with the old style lamps.

Having thus described my invention, what I claim and desire to secure by Letters Patent is:

1. In an apparatus of the character described, a socket member, a bracket member removably associated with said socket member, said bracket member having electric circuit terminals, said socket member having electric circuit terminals, a movable switch having circuit closer elements, and means operative upon bringing said bracket and socket members together for first throwing said 125

switch to close the circuit between its closer elements and the circuit terminals of said socket and thereafter to close the circuit between said bracket member's circuit terminals and said circuit closer.

5 2. In an apparatus of the character described, a socket member, a bracket member removably associated with said socket member, said bracket member having electric circuit terminals, said socket member having electric circuit terminals, a movable switch having circuit closer elements, means operative upon bringing said bracket and socket members together for first throwing said switch to close the circuit between its closer elements and the circuit terminals of said socket and thereafter to close the circuit between said bracket member's circuit terminals and said circuit closer elements, and operable upon separating said bracket and socket members to restore the switch parts and circuit terminals to their initial position.

10 3. In apparatus of the class described, a socket member and a bracket member having mating parts; fixed electric circuit contact members carried by each said socket and bracket members; a movable switch carried by one of said members and having contacts to cooperate with the respective contact members of said socket and bracket members; means holding said switch in a circuit-open position when said mating parts are disengaged; and means operable upon partially engaging the mating parts to throw said switch to bridge the circuit between said contact members of said socket member and the contacts of said switch and upon completely engaging said mating parts bring said switch contacts and those of said bracket member into engagement.

15 4. In apparatus of the class described, a socket member and a bracket member having mating parts; fixed electric circuit contact members carried by each said socket and bracket members; a movable switch carried by one of said members and having contacts to cooperate with the respective contact members of said socket and bracket members; means holding said switch in a circuit-open position when said mating parts are disengaged; means operable upon engaging the mating parts to throw said switch to bridge the circuit between said contact members of said socket member and those of said bracket member; said switch comprising a face plate, an insulator secured to the back of the same, circuit contact elements on said insulator and trunnions for pivotally mounting said switch.

20 5. In apparatus of the class described, a socket member and a bracket member having mating parts; fixed electric circuit contact members carried by each said socket and bracket members; a movable switch carried

by one of said members and having contacts to cooperate with the respective contact members of said socket and bracket members; means holding said switch in a circuit-open position when said mating parts are disengaged; and means operable upon engaging the mating parts to throw said switch to bridge the circuit between said contact members of said socket member and those of said bracket member; said switch comprising a face plate, an insulator, contact elements and trunnions; said socket member having a slotted base plate in the slot of which said face plate normally lies; said switch holding means comprising a stop and a spring-toggle device.

25 6. In apparatus of the class described, a socket member and a bracket member having mating parts; fixed electric circuit contact members carried by each said socket and bracket members; a movable switch carried by one of said members and having contacts to cooperate with the respective contact members of said socket and bracket members; means holding said switch in a circuit-open position when said mating parts are disengaged; means operable upon engaging the mating parts to throw said switch to bridge the circuit between said contact members of said socket member and those of said bracket member; said switch comprising a face plate, an insulator, contact elements and trunnions; said socket member having a slotted base plate in the slot of which said face plate normally lies; said switch holding means comprising a stop and a spring-toggle device, and said switch throwing means comprising projections on the front of said face plate which are adapted to be engaged by the mating element of said bracket member.

30 7. In apparatus of the class described, a socket member comprising a base plate, a socket projecting from the front face of said base plate and having a recess to receive a mating element of a lamp bracket; a pair of insulated and relatively fixed circuit contact members mounted on said base plate, said base plate having a slot and having bearing elements; a switch member pivotally mounted in said bearing elements and itself including a face plate adapted normally to lie in and constitute a closure for said slot, said switch member also including an insulator and circuit contact elements carried thereby and adapted to engage with and to be disengaged from said relatively fixed contact members accordingly as said switch is in one position or another; and means operable by engagement of the mating element of a lamp bracket to throw said switch from one position to another.

35 8. In apparatus of the class described, a socket member comprising a base plate, a socket projecting from a face of said base plate and having a recess to receive a mating

element of a lamp bracket; a pair of insulated and relatively fixed circuit contact members mounted on said base plate, said base plate having a slot and having bearing elements; a switch member pivotally mounted in said bearing elements and itself including a face plate adapted normally to lie in and constitute a closure for said slot, said switch member also including an insulator and circuit contact elements carried thereby and adapted to engage with and to be disengaged from said relatively fixed contact members accordingly as said switch is in one position or another; and means operable by engagement of the mating element of a lamp bracket to throw said switch from one position to another, and including a toggle rod and spring device to effect a quick action of the switch.

9. In apparatus of the class described, a socket member comprising a base plate, a socket projecting from a face of said base plate and having a recess to receive a mating element of a lamp bracket; a pair of insulated and relatively fixed circuit contact members mounted on said base plate, said base plate having a slot and having bearing elements; a switch member pivotally mounted in said bearing elements and itself including a face plate adapted normally to lie in and constitute a closure for said slot, said switch member also including an insulator and circuit contact elements carried thereby and adapted to engage with and to be disengaged from said relatively fixed contact members accordingly as said switch is in one position or another; and means operable by engagement of the mating element of a lamp bracket to throw said switch from one position to another; in combination with a bracket having relatively fixed circuit contact members with fingers adapted to engage the switch's contact elements after the switch has been thrown to the circuit-closed position.

10. In apparatus of the class described, a socket member comprising a base plate, a socket projecting from a face of said base plate and having a recess to receive a mating element of a lamp bracket; a pair of insulated and relatively fixed circuit contact members mounted on said base plate, said base plate having a slot and having bearing elements; a switch member pivotally mounted in said bearing elements and itself including a face plate adapted normally to lie in and constitute a closure of said slot, said switch member also including an insulator and circuit contact elements carried thereby and adapted to engage with and to be disengaged from said relatively fixed contact members accordingly as said switch is in one position or another; and means operable by engagement of the mating element of a lamp bracket to throw said switch from one position to another, and including a toggle rod and

spring device to effect a quick action of the switch; in combination with a bracket having relatively fixed circuit contact members with fingers adapted to engage the switch's contact elements after the switch has been thrown to the circuit-closed position.

11. In apparatus of the class described, a socket member comprising a base plate, a socket projecting from a face of said base plate and having a recess to receive a mating element of a lamp bracket; a pair of insulated and relatively fixed circuit contact members mounted on said base plate, said base plate having a slot and having bearing elements; a switch member pivotally mounted in said bearing elements and itself including a face plate adapted normally to lie in and constitute a closure for said slot, said switch member also including an insulator and circuit contact elements carried thereby and adapted to engage with and to be disengaged from said relatively fixed contact members accordingly as said switch is in one position or another; and means operable by engagement of the mating element of a lamp bracket to throw said switch from one position to another, and including a toggle rod and spring device to effect a quick action of the switch; in combination with a bracket having relatively fixed circuit contact members with fingers adapted to engage the switch's contact elements after the switch has been thrown to the circuit-closed position, said bracket and said socket members having lost motion upon being assembled whereby engagement of the bracket member's fingers with the switch's contact elements will be effected after the switch has been completely thrown to the circuit-closed position and disengagement will occur before the switch is thrown to the circuit-open position.

12. In apparatus of the class described, a bracket member and a socket member, said members having engaging parts, each member having relatively fixed circuit terminals, combined with a switch for bridging said terminals when said members have been assembled, means to mount said switch on one of said members and throw it by the other member, and a quick action device to complete the throwing of the switch after the same shall have been initiated by said other member, a housing for said switch, said housing having a slot and said switch having a part constituting a closure for said slot when the said members have been separated.

13. In an apparatus of the class described, a socket member, a bracket member removably associated with said socket member, said bracket member having electric circuit terminals, said socket member having electric circuit terminals, a movable switch having circuit closer elements, means operative upon bringing said bracket and socket members together for first throwing said switch to

close the circuit between its closer elements and the circuit terminals of said socket and thereafter to close the circuit between said bracket member's circuit terminals and said circuit closer, and a quick-action device to complete the throwing of the switch after the same shall have been initiated by the bringing together of said bracket and socket members.

10 Signed at the city of New York, in the county of New York, and State of New York, this 30th day of December, 1927.

LAURITS C. EICHNER.
